UNITED STATES PATENT OFFICE

PERCY THREADGILL, OF BURNSVILLE, NORTH CAROLINA, ASSIGNOR TO CELO PROPERTIES, INC., OF MIAMI, FLORIDA, A CORPORATION OF FLORIDA

BUILDING

Application filed May 16, 1929. Serial No. 363,598.

The present invention relates to improvements in building construction, and may be embodied in walls, floors, and ceilings of dwelling houses or commercial structures.

8 An object of the invention is to provide a light construction of great strength possessing water-resisting qualities, and which will be fireproof.

Another object of the invention is to provide a construction which may be ready-cut and prepared at the source of manufacture, and upon being shipped to the scene of building operations, readily and correctly assembled by unskilled labor.

15 The construction possesses not only lightness, but a great strength, and when assembled, provides a very nice interior and exterior finish which will be satisfactory in appearance, or which may be treated or decorated as desired.

Referring to the drawings:

Figure 1 is a perspective view partly broken away, of a wall embodying my invention.

25 Figure 2 is a vertical section.

Figure 3 is a perspective of a modification, and

Figure 4 is a perspective of a further modification.

30 In carrying out the invention, which may be applied to a wall, ceiling, floor or other part of a building, it will be understood that it is preferably constructed of slabs or bricks of suitable dimension which may be formed 35 of soapstone, serpentine, marble, or molded of concrete or other compound plastic, and incidentally wall-board may be utilized, there being many varieties of this latter material on the market.

40 In the drawings I have illustrated the invention applied to a vertically extending wall, but its application to parts of a building disposed horizontally or angularly, will be readily understood.

45 The wall shown in Figure 1 is formed of two spaced parallel elements 10 and 11. These elements are comprised of slabs 12 arranged in courses, as is well-known in brick masonry.

50 Each of the slabs 12 upon one of its lon-

gitudinal edges is provided with a plurality of pins or projections 13, as shown in Figure 2. On the opposite edge, each slab is provided with a plurality of recesses or sockets 14. In Figure 1 I have shown each slab provided with a pair of pins adjacent its ends and two pairs of pins intermediate the slab. It will be understood that a similar arrangement of recesses will be provided on the lower edge of each slab. The number of pins employed may be departed from, and the pins may either be fixed to a slab or loosely positioned therein. It will be understood, however, that these pins serve to align the slabs and also to hold them fixed while the structure is being formed. The slabs, of course, are preferably plastered or cemented, as is well-known in bricklaying.

55 In the space between the elements, there are positioned pairs of slabs 15. These pairs of slabs are preferably disposed adjacent the meeting ends of the bricks of the several courses. For example, in Figure 1 the first pair of slabs is shown adjacent the joint 16, 60 17, while the second pair of slabs is disposed upon opposite sides of a similar jointure in the element 11. This means of spacing the slabs 15 is followed except at the corners where but a single slab 18 need be utilized.

65 The slabs are positioned in the space between the elements and a metal band or a wire 19 is drawn about the pins or projections 13, after the manner shown in Figure 1, to form a ring or encircling band for the transverse slabs 15. In the case of a wire, it will only be necessary to use a single strand and wind it about the pins 13. However, separate strands may be used to engage each transverse slab 15, and if desired, all of the transverse slabs may be joined by a single strand of wire which will run from one end of the structure to the other. The slabs 15 are preferably of a width just sufficient to fit within the space between the elements, and the binding means 19 will serve not only to support the slabs 15 in position, but also as a binding means for the two elements, acting to maintain them in proper position and 80

85 against the side edges of the transverse slabs 15. 90 95 100

The space defined by the transverse slabs and the two elements forms a pouring space into which, when the wall has reached a sufficient height, is poured concrete or cement. 5 When this has been allowed to harden, there is provided a plurality of columns forming a staunch and dependable support for a wall, floor, ceiling, or angularly disposed structure, and in addition, the concrete or 10 cement will act to bind or unite all of the slabs together. In this manner the columns are disposed at the joints between the slabs to act as an additional reinforcement for the plaster as well as the wire or metal strand 15 or band when a continuous piece of material is employed, and the two elements are firmly united to the pairs of transverse slabs. Thus a complete supporting structure in the form of the columns, which will be indicated at 20, 20 is provided, at the same time acting to bind the slabs of each element, and to bind the elements to the transverse slabs.

In addition, it will be noted that a construction much more satisfactory than the usual 25 hollow tile expedient is provided, since by the present invention a very adequate support is given, and at the same time lightness is afforded.

In Figure 3 I have shown the use of single 30 pins, as distinguished from pairs of projections 13, with a single metal band or wire extending about each transverse slab 15 and over the pins 13.

In Figure 4 I have shown the strands 19 35 as extending through openings in the slabs 12 and about the transverse slabs 15. In this embodiment, wire may be utilized and joined at the ends as shown or a metal band may be employed. In this connection it will be understood that if found desirable, the wire or bands may be removed.

While I have illustrated the use of metal bands or wires encircling each transverse slab and united to pins carried by the slabs of the 45 elements, or, as in Figure 4, the wires extending transversely through the slabs of the elements, it will be understood that I may recess the interior walls of the slabs of the elements and loosely position a band of metal in such 50 recesses to enclose the transverse slabs.

It will, moreover, be understood that all of the slab work may be ready cut and shipped in that form to the building operation and that the pins and recesses not only align the 55 slabs of the courses, but likewise fix the position of the transverse slabs.

The construction has been found effective and permits the erection of buildings at relatively small cost, since a variety of cheap 60 material can be employed and assembled without the necessity of skilled labor.

In assembling a corner, where the slabs extend at right angles to each other, one of the exterior courses of slabs may be disposed so 65 as to form a complement to the adjacent trans-

verse slab and provide the pouring space. This is shown in Figure 1.

On the other hand, one of the inner courses may be extended to form the transverse complement of the outer slab, so that at the corner 70 there will, in effect, be no transverse slab. In each case, however, the pins and binding bands will be arranged about the several slabs in the manner shown in Figure 1, so as to effectively hold the several members together 75 as well as provide for aligning of the upper and lower courses.

In this connection, it should also be stated that the transverse slabs are provided with pins and recesses after the manner of the 80 slabs of the other courses for example as shown in Figure 1 and for a similar purpose.

In the claims appended hereto, it will be understood that their scope is intended to cover alterations and modifications which 85 may be made without departing from the spirit of this invention.

I claim:

1. In a building, the combination of two spaced structural elements formed of 90 courses of slabs, projections on the slabs engaging in recesses of adjacent slabs, pairs of slabs disposed transversely in the space between the elements and on opposite sides of the meeting edges of the slabs of each element, said transverse slabs forming with the elements a pouring space, and a cementitious medium disposed in said pouring space forming a supporting column and binding all of 95 the slabs and elements together. 100

2. In a building, the combination of two spaced structural elements formed of courses of slabs, projections on the slabs adjacent and intermediate their ends, engaging in recesses of adjacent slabs, pairs of slabs 105 disposed transversely in the space between the elements and on opposite sides of the meeting edges of the slabs of each course, said slabs forming a pouring space, and a cementitious medium disposed in said pouring 110 space forming a supporting column and binding all of the slabs and elements together. 110

3. In a building, the combination of two spaced structural elements formed of courses 115 of slabs, pairs of slabs disposed transversely in the space between the elements, means carried by the elements for supporting said transverse slabs, said transverse slabs forming with the elements a pouring space, and a cementitious medium disposed in said pouring space forming a supporting column and binding all of the slabs and elements together. 120

4. In a building, the combination of two spaced structural elements formed of courses of slabs, pairs of slabs disposed transversely in the space between the elements and on opposite sides of the meeting edges of the slabs of each course, means carried by the elements 125 130

for supporting said transverse slabs, said transverse slabs and said elements forming a pouring space, and a cementitious medium disposed in said pouring space forming a supporting column and binding all of the slabs and elements together.

5. In a building, the combination of two spaced structural elements formed of courses of slabs, projections on the slabs engaging in recesses of adjacent slabs, pairs of slabs disposed transversely in the space between the elements, means engaging said projections and adapted to support said transverse slabs, said transverse slabs and elements forming a pouring space, and a cementitious medium disposed in said pouring space forming a supporting column and binding all of the slabs and elements together.

10. In a building, the combination of two spaced structural elements formed of courses of slabs, projections on the slabs engaging in recesses of adjacent slabs, said projections and recesses being formed in opposite side edges of each slab and adjacent and intermediate the ends thereof, pairs of slabs disposed transversely in the space between the elements, and forming therewith a pouring space, a metallic strand engaging about said projections and transverse slabs for supporting the slabs in position, and binding the slabs of the elements to said transverse slabs, said transverse slabs being disposed upon opposite sides of the meeting edges of the slabs of each course, and a cementitious medium disposed in said pouring space forming a supporting column and binding all of the slabs and elements together.

15. In a building, the combination of two spaced structural elements formed of courses of slabs, each having spaced recesses formed in the edges of the slabs adjacent and intermediate the ends thereof, pairs of spaced slabs disposed transversely in the space between the elements and forming therebetween a pouring space, pins engaging in the recesses of the slabs of the courses, and metallic strands engaging about said pins and said transverse slabs for holding the transverse slabs in place, said transverse slabs being disposed upon opposite sides of the meeting edges of the slabs of each course, and a cementitious material disposed in said pouring space forming a supporting column and binding all the slabs and elements together.

20. In testimony whereof I have hereunto set my hand.

PERCY THREADGILL.
